MAX KLINE, OF BRONX, AND MAX KAPLAN, OF NEW YORK, N. Y., ASSIGNEES TO
SUPERIOR PRODUCTS CORPORATION, OF ELIZABETH, NEW JERSEY, A CORPORATION
OF NEW JERSEY

VANITY CASE

Application filed January 15, 1930. Serial No. 420,834.

This invention relates to improvements in toilet accessories, and more particularly to thin flat ornamental containers for face powder and the puff used in its application.

Such containers have usually been constructed of a large number of parts, requiring expert mechanical skill in their construction and assembly, and due to their construction offer but slight resistance to compression, therefore being easily subject to rupture and destruction.

It is an object of the present invention to provide a structure comprised of few and simple parts, all readily amenable to usual processes of manufacture and which after assembly constitute a secure means for containing the powder, puff and also a mirror in a neat and highly attractive manner.

A further feature is in a provision of means whereby the hinged elements are at least partially integral with the lid or cover of the container, thereby tending to produce an unusually strong and effective device.

Another aim is to provide a container for the powder so arranged as to prevent its escape for the inner receptacle provided for it.

These and other advantageous objects are accomplished by the novel construction, arrangement and combination of parts hereinafter described and shown in the accompanying drawing, constituting an essential element of this disclosure, and in which:

Fig. 1, is a perspective view of a complete embodiment of the device, the lid being shown in a partial raised position.

Fig. 2, is a transverse sectional view, taken through the hinge and clip elements, and drawn to an enlarged scale.

Fig. 3, is a fragmentary sectional view taken through the rim and showing the lid in closed position.

Fig. 4, is an expanded sectional view showing the elements of the lid prior to assembling.

Fig. 5, is a similar expanded view showing the elements constituting the body of the container.

As shown throughout the several drawings, the lid or cover element is composed of a sheet

of suitable material, preferably thin metal, although celluloid or like substances may be used, as preferred.

This lid is struck or stamped to produce an arcuately curved top 10, its edges blending into a raised annular body 11 having a down-turned annular flange 12 of uniform height, this flange being notched upon opposite sides as at 13.

Fitted to seat upon the inner peripheral edge 14 of the cover 10 is a cardboard disc 15, acting as a packing or cushion for a circular mirror 16, which together with the element 15, are closely contained within the down-turned flange 12.

The lower element of the cover consists of a stamped ring 17 having an inwardly bent flange 18, the edge of which is adapted to contact the margin of the mirror 16, holding it in firm engagement within the outer element of the cover.

Integrally formed with the ring 17 is a flange 19 having an extending strip 23 coiled to present an eye 20, constituting one of the hinge members, and directly opposite the strip is a finger clip 21 adapted for use in opening or closing the cover.

The elements 21-23 are suited to neatly engage in the notches 13 of the upper element, while the flange 12 may be spun or rolled to engage the ring 17 thus maintaining the parts in fixed relation. A node 22 may be formed on the ring 17 in register with the clip 21 to act as a locking member, as will later be seen.

The body or main portion of the container is composed of a cylindrical ring 25 die formed from sheet material, the upper edge of the ring being outturned and curved downwardly, presenting a substantially bevelled surface 26, which may be ornamented in any desired manner, and at the edges of the element 26 is a downturned annular flange 27 of uniform height with the bottom of the ring 25, from which it is spaced concentrically therewith.

An opening in the element 26 is provided to receive the flange elements 28 of an eye 29, recessed to receive the eye 20 of the cover and

which is held rigidly when assembled by spreading the flanges 28 in a manner which will be well understood, a hinge pin 24 of the usual type being passed through the eyes.

5 A second ring 30 is formed with a diameter adapted to be forced over the element 25, the lower edges of which are integral with the peripheral edge of an arcuately curved cup 31, which constitutes the bottom of the powder 70 receiving receptacle.

The lowermost element of the container is composed of an arcuately curved shell 32, its marginal periphery 33 being offset upwardly so that its edge will enter into the space 15 bounded by the flange wall 27, which is thereafter spun or coiled inwardly producing a smooth, imperceptible joint, as at 34, and binding the body elements into rigid relation.

An indentation 35, in the cylinder at a 20 point directly opposite the hinge element 20, receives the projection 22 of the cover element, forming a snap catch or lock, easily released by actuating the clip 21, it being understood that the nature of the material and their 25 shape is such as to permit of the limiting springing movement necessary for the catch to operate.

From the foregoing it will be seen that the container presented is such as to permit of 30 any desired surface ornamentation, and further that the shape is such as to resist compressive and destructive strains to an unusual degree.

The powder container is adapted to prevent 35 powder from escaping, while the mirror is held in a substantial manner.

It is to be noted that no solder is used in the construction, the parts all being constructed and assembled by purely mechanical action.

40 Although the foregoing is the best known embodiment of the device, it is obvious that minor changes may be made without affecting the spirit of the invention or the claims by which it is defined.

45 Having thus described the invention, which is claimed as new and desired to secure by Letters Patent, is:

1. A container comprising an arcuate bottom plate having a recessed annular margin, 50 a ring having a part engaged in the recess and bent re-entrantly to constitute the edge of the container, said ring having an overlying annular element constituting a fixed part of the container top, a cylindrical flange at 55 the inner edge of the annular element extending towards said bottom plate, a cup resting on said plate and having a raised peripheral flange tightly engaged in said cylindrical flange, hinge eyes set in the overlying element of said ring, an arcuately curved cover, 60 a hinge eye integral with the edge of said cover to engage the first named hinge eyes, a clip opposite the hinge eyes, and resilient means for detachably securing said cover 65 when in a closed position.

2. In a container for powdered material, a pair of hingedly engaged elements constituting a body and cover therefor, said cover elements having one of the hinge members formed integral therewith, a cup fixed centrally in the body element, means on said body to prevent escape of material from said cup, a mirror carried by said cover, and means for removably securing the cover to the body when closed thereover. 75

3. In a container for powdered material, a pair of hingedly engaged elements constituting a body and cover therefor, said cover element having one of the hinge members formed integral therewith, a cup fixed centrally in the body element, means on said body to prevent escape of material from said cup, a mirror, a ring fixed in said cover to retain said mirror permanently therein, said ring and mirror forming a cover for said 80 cup, resilient means for detachably securing the cover when closed over the body, and a clip on said ring to facilitate operation of said securing means. 85

4. In a container for powdered material, 90 a pair of hingedly engaged elements constituting a body and cover therefor, a ring permanently engaged in said cover, one of said hinge members being integral with said ring within the cover, a cup in said body, and 95 means to retain said cup rigidly therewith, same means also preventing escape of the contents of said cup. 100

5. In a container for powdered material, a pair of hingedly engaged elements constituting a body and cover therefor, an annular ring having inreaching flanged edges, one of said flanges forming a fixed portion of the container body and the other flange set in a peripheral recess in the lowermost body element, a ring set rigidly in the cover element, one of the hinge members being integral with said ring, said rings co-operating to form a tight closure for said cup, a snap fastener engaging said rings opposite the hinge, and a clip on said ring for releasing 110 said fastener. 105

Signed at New York, in the county, city, and State of New York, this 3rd day of January, 1930.

115
MAX KLINE.
